UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

ROCK-DRILLING MACHINE.

1,097,224.

Specification of Letters Patent. Patented May 19, 1914.

Application filed September 9, 1910. Serial No. 581,198.

To all whom it may concern:

Be it known that I, CHARLES C. HANSEN, a citizen of the United States, and resident of Easton, in the county of Northampton and State of Pennsylvania, have invented a new and useful Improvement in Rock-Drilling Machines, of which the following is a specification.

This invention relates to improvements in rock-drilling machines and has for its object to provide a suitable support such, for instance, as a wagon, a turntable thereon, a frame uprising from the turntable arranged to carry a tool of any character, such as a 10 rock drill, the rock drill being movable up and down along the frame.

A further object is to provide a device of this character in which a common means is utilized for propelling the wagon, swinging 20 the turntable and controlling the movements of the rock drill.

In the accompanying drawings, Figure 1 represents the machine partially in side elevation and partially in vertical central section, Fig. 2 is a top plan view of the machine, and Fig. 3 is a detail horizontal section showing some of the driving connections between the engine and the parts controlled thereby.

30 The turntable is denoted by 1 and its track by 2. An annular series of balls 3 is interposed between the turntable and track, forming a roller bearing for the turntable. The support for the turntable in the present instance comprises a wagon having a platform 4, framework 5 and traction wheels 6. A fixed frame uprises from the turntable, which frame comprises horizontal base members 7, vertical members 8 and diagonal 35 members 9.

The rock drill is denoted by 10 and its saddle by 11. This saddle is fitted to move up and down along the vertical members of the frame. In the present instance the rock drill 45 is fed downwardly to its work by gravity. A reversing hoisting engine 12 is mounted on the wagon platform. This engine is provided with a winding drum 13 from which the hoisting cable leads under pulleys 15, 16, 50 17, 18, on the wagon; from thence upwardly through the center of the turntable and over pulleys 19, 20, at the top of the frame. From thence the cable passes downwardly around pulleys 21, 22, carried by the drill saddle 11; 55 thence upwardly around a pulley 23 at the

top of the frame. This engine 12 also serves to swing the turntable into its different positions as follows: The turntable is provided on its periphery with teeth 24 which mesh with a pinion 25 on a vertical shaft 26, 60 which shaft also has a beveled gear connection 27, 28, with a horizontally arranged shaft 29 mounted in the wagon frame. This shaft 29 is provided with a bevel gear 30 and a cross shaft 31 is provided with a bevel gear 65 32 which may be brought into and out of engagement with the bevel gear 30 by a hand clutch lever 33. This cross shaft 31 is further provided with a chain and sprocket connection 34, 35, 36, with the engine shaft 37. 70 This engine 12 is also arranged to propel the wagon in either direction as follows:—One pair of traction wheels 6 is connected to the engine shaft 37 through sprockets 38, 39, chain 40; sprockets 41, 42, chain 43; and 75 gears 44, 45. A hand operated clutch 46 is arranged to connect and disconnect the gear 45 and the sprocket 42. Suitable clamps 47 are provided for locking the turntable in its different positions.

80 To insure a rigid support for the machine during the drilling operation, the base members 7 of the drill supporting frame are projected outwardly a distance beyond the wagon and at their ends they are provided with one or more adjustable braces 48 (in the present instance two braces) which are herein shown in the form of screw jacks arranged to be screwed down into engagement with the ground.

85 In operation, the wagon is moved to the point where the drilling operation is to be carried out by connecting the engine to the traction wheels. The engine is then utilized for swinging the turntable to the desired 90 point where it may be locked by the clamps 47. The engine is then connected to the drill and the drill is permitted to be fed by gravity to its work. After the hole has been drilled, the engine may be used for 100 lifting the drill. It may then be used for swinging the turntable into another position or it may be used for moving the wagon to another position, as desired.

105 It will thus be seen that a very simple means is employed for carrying out the several operations herein described.

While I have chosen to show and describe my invention in connection with a rock drill movable along the frame, it is to be under- 110

stood that a tool of any character may be employed without departing from the scope of my invention. It is also evident that various changes might be resorted to in the 5 construction, form and arrangement of the several parts without departing from the spirit and scope of my invention; hence I do not wish to limit myself strictly to the structure herein set forth, but

10 What I claim is:—

1. A wagon, a turntable thereon, a frame 15 uprising from the turntable, a rock drill movable along the frame and an engine mounted on the wagon arranged to propel the wagon and to swing the turntable.

2. A wagon, a frame carried thereby, a 20 rock drill movable along the frame and an engine mounted on the wagon arranged to propel the wagon and to control the movements of the rock drill.

3. A wagon, a turntable thereon, a frame 25 uprising from the turntable, a rock drill

movable along the frame and an engine mounted on the wagon arranged to propel the wagon to swing the turntable and to 25 control the movements of the rock drill.

4. A wagon, a turntable thereon, a frame 30 uprising from the turntable and projecting beyond the wagon, one or more adjustable braces depending from the projecting portion of the frame, a rock drill movable along the frame and an engine mounted on the wagon arranged to propel the wagon to swing the turntable and control the movements of the rock drill. 35

In testimony, that I claim the foregoing as my invention, I have signed my name in presence of two witnesses, this first day of September 1910.

CHARLES C. HANSEN.
